Term of patent 14 years

Int. Cl. D26—03; D8—03

U.S. Cl. D48—31

Fig. 3

FIG. 1 is a side elevational view of a combined yard lamp and identification sign, showing my design the opposite side being substantially the same in appearance,

FIG. 2 is an edge elevational view of the yard lamp and sign as shown in FIG. 1, and

FIG. 3 is a top plan view of the yard lamp and sign.

The post is broken away in FIGS. 1 and 2 to show indeterminate length.

The indicia is shown in broken lines in FIG. 1 for illustrative purposes only.

I claim:

The ornamental design for a combined yard lamp and identification sign, as shown and described.
